(57) **CLAIM**

The ornamental design for a flow passage member for pressure sensor, as shown and described.

DESCRIPTION

FIG. 1 is a front view of the flow passage member.

FIG. 2 is a rear view of the flow passage member.

FIG. 3 is a top view of the flow passage member.

FIG. 4 is a bottom view of the flow passage member.

FIG. 5 is a right side view of the flow passage member.

FIG. 6 is a left side view of the flow passage member.

FIG. 7 is a sectional view of the flow passage member as viewed along line A-A in FIG. 1.

FIG. 8 is a perspective view of the flow passage member; and,

FIG. 9 is a reference perspective view of the flow passage member and the pressure sensor.

The broken lines in the drawings depict environmental structure which forms no part of the claimed design.
